UNITED STATES PATENT OFFICE

NATHAN M. LOWER, LONNIE EDWARD OSBORNE, AND EDWIN ARCHER TURNER, OF PITTSBURGH, PENNSYLVANIA, ASSIGNEES, BY MESNE ASSIGNMENTS, TO THE STANDARD STOKER COMPANY INC., OF NEW YORK, N. Y., A CORPORATION OF DELAWARE

INSIDE FEED STOKER

Application filed January 8, 1926. Serial No. 79,976.

This invention relates to stokers for steam boilers, and more particularly to stokers for locomotives and the like.

One of the objects of the invention is the provision of new and improved means for transferring fuel from the tender of a locomotive and delivering the same in a plurality of streams to the firebox through the grates thereof.

10 Another object of the invention is the provision of new and improved means for transferring the fuel from the conveyer to the firebox.

15 A further object of the invention is the provision of new and improved means for operating the stoker mechanism together with new and improved means whereby the fuel transferring screws may be removed from their casings or conduits.

20 A still further object of the invention is the provision of new and improved means for protecting the exposed upper ends of the fuel transfer casings from the intense heat of the burning fuel.

25 Another object of the invention is the provision of a new and improved stoker that is cheap to manufacture, easily assembled, efficient in operation, light in weight and composed of few moving parts.

30 Other and further objects and advantages of the invention will appear from the following description taken in connection with the accompanying drawings, in which—

Fig. 1 is a side elevation of a portion of a locomotive and tender showing the invention in position thereon, with parts in section and parts broken away;

Fig. 2 is a plan view of the forward portion of a stoker, with parts in section and parts broken away, and showing a portion of the locomotive in horizontal section;

Fig. 3 is a section on line 3—3 of Fig. 2;

Fig. 4 is a section on line 4—4 of Fig. 2;

45 Fig. 5 is a side elevation of a portion of a locomotive showing a modified form of transfer conduit, with parts broken away;

Fig. 6 is a horizontal section of a modified form of a portion of the stoker mechanism;

50 Fig. 7 is a horizontal section showing a

modified form of protecting member for the exposed portion of the transfer conduit.

On the drawings the reference character 10 designates a locomotive, and 11 the tender therefor. The locomotive comprises the 55 backhead 12, the firebox 13 and the grates 14, all of which are of the usual or of any approved construction.

The stoker mechanism for conveying the fuel from the tender and transferring it to 60 the firebox of the locomotive comprises the conveyer 15 and the transfer members 16 and 17. The conveyer 15 comprises a casing extending from the tender to the locomotive. In the form shown, it comprises a sectional 65 casing 18 the rear end of which is in the form of a trough located beneath a suitable opening in the bottom of the fuel tank 19 of the tender 11 for receiving the fuel from said tank as is usual in such constructions. 70

The casing 18 is preferably though not necessarily enlarged as at 21 and the front end of the enlargement is connected to the front section 22 of the conveyer casing by a universal joint 23. The conveyer casing is 75 provided with a sectional conveyer screw 24. The forward end of the rear section of this screw has its flight considerably increased in diameter as at 25 for operating in the enlargement 21. The forward section 26 of the conveyer screw may, if desired, be provided with a double flight 30 for more evenly distributing the fuel to the two transverse casings. The forward ends of the two flights extend radially on opposite sides of the shaft and in the plane thereof for preventing the conveyer screw from wedging the fuel against the forward end of the conveyer casing. The section 26 is preferably journaled in the casing 22 at its forward end and 80 is connected to the rear section of the conveyer screw by a universal joint 27 which is in vertical alignment with the joint 23 whereby the sections of the conveyer may move more angularly relative to each other. 85

A plurality of transfer members are used for transferring the fuel from the conveyer to the firebox. As shown, a pair of these members are employed. They diverge forwardly and their rear ends are united and are 90 95 100

located beneath the forward end of the conveyer screw. These members comprise the casings 27 and 28 in which are movably mounted two fuel transfer members 29 and 31. The members 29 and 31 are preferably, though not necessarily, helicoid screws rotatably mounted in said casings. Each of the casings 27 and 28 is preferably made in two or more sections. As shown they are split horizontally along their longitudinal center line. The upper sections of the casings are preferably rigidly connected to the forward section 22 of the conveyer casing. The sections of the transfer casings are held together by any suitable means as the bolts 32. By means of this arrangement the transfer screws may be removed by first removing the lower sections of the casing.

The forward section 22 of the conveyer casing is enlarged laterally and its lower wall is preferably, though not necessarily, cast integral with the upper sections of the casings 27 and 28. The common wall between the casings is provided with oblong openings 33 and 34 adjacent to the rear ends of the conveyer screws 29 and 31, respectively. In the form of the device shown on the drawings the openings 33 and 34 are above the conveyer screws 29 and 31, whereby fuel delivered from the casing 22 will fall by gravity into the transfer casings 27 and 28.

As shown in Figs. 1 to 4 the transfer casings extend forwardly and upwardly and their forward portions are curved and extend upwardly through the grates in each of the back corners of the firebox to a substantial distance above said grates. The upwardly extending portions 35 and 36 of the casings 27 and 28 are detachably connected to the lower portions as by means of suitable lugs and bolts 290, as clearly shown in Fig. 1.

In order to protect the exposed upper ends of the casings 27 and 28 from the heat of the burning fuel, a wall of water pipes is extended about the same. Preferably a series of pipes 37, each having its ends secured in the back wall of the boiler, are employed. One end of each pipe is placed at a higher level than the other end, thereby insuring free circulation of water therethrough from and into the boiler. The upper casing sections 35 and 36 may if desired be provided with flanges 38 at their upper ends for engaging over the pipes 37. A nozzle 40 is located in each corner of the firebox in rear of the casings for delivering a blast against the fuel as it is forced above the ends of the casings for distributing the same in the firebox.

Suitable means are provided for operating the conveyer and transfer screws. As shown, a motor 39 which is preferably in the form of a four cylinder steam engine having the intake and exhaust ports 41 and 42 in common, is employed. The piping is omitted for the sake of clearness.

The conveyer and elevator screws are all operated from a sectional shaft that is connected to the crank shaft 44 either directly or through a system of reducing gears. As shown, the engine extends transversely of the locomotive, and an elongated bearing or casing 45 is secured thereto and extends beneath the conveyer to which it is rigidly connected. A shaft 46 provided with worms 47 and 48 for engaging the gears 49 and 51 on the shafts of the transfer screws 29 and 31 respectively, is mounted in the bearing 45. The threads of the screws 47 and 48 are in opposite directions whereby the thrust of each will be counteracted by the other. A sleeve 52 connects the adjacent squared ends of the shafts 44 and 46.

The conveyer screw is operated from the shaft 44 through the worm 54 on the sleeve 58, gear 55 and shaft 56 which operates gearing 57 at the rear end of the conveyer screw in the usual manner. The housing for the gear 55 is preferably integral with or rigidly secured to the casing or bearing 45.

It is desirable that the driving mechanism be so constructed that the transfer screws may be operated independently of the conveyer screw. This is accomplished by providing a sleeve clutch 57 slidably but non-rotatably mounted on the squared end of the shaft 46 which is adapted to be slid into interlocking connection with the sleeve 58 rotatably mounted on the reduced end of shaft 46 or disengaged therefrom by means of the shifter member 59 as clearly shown in Fig. 3. The sleeve 58 is prevented from moving inwardly by the shoulder formed at the end of the reduced portion, and from moving outwardly by the bearing 70 seated in the end cover member. A suitable operating member for the shifter member 59 extends adjacent to a convenient position for the fireman. For the sake of clearness in illustration this operating member is omitted.

In the operation of the device, the fuel from the tank 19 falls into the conveyer trough and is conveyed forwardly by the screw 24. The enlarged portion 21 of the casing permits the fuel to loosen up whereby the double flight of the screw section 26 will deliver it evenly to the two transfer screws which will force it upward into the rear corners of the firebox in front of the blasts from the nozzles 40 for distributing it over the grates.

In Fig. 5 is shown a modified form of transfer conduits in which the detachable end sections 61 thereof terminate on the plane of the grates 62. In this form of the device the nozzle 63 is elevated above the member 61 whereby fuel will be permitted to pile up in the corners a sufficient distance before coming into the zone of action of the blasts.

In Fig. 7 is shown a modified form of protector member for the upper ends of the

transfer tubes or conduits where they extend above the grates. In this form of the device spaced walls 64 and 65 are provided which extend about the casings 36 in a manner similar to the tubes shown in Figs. 1 to 4.

In Fig. 6 is shown a modified construction in which the front section 26 of the conveyer screw as employed in Figs. 1 to 4 is eliminated and the casing is provided with a di-
10 vider .66 which divides the fuel into two streams for the transfer screws 29 and 31.

It is thought from the foregoing taken in connection with the accompanying drawings that the construction and operation of our
15 device will be apparent to those skilled in the art, and that various changes in size, shape, proportion and details of construction may be made without departing from the spirit and scope of the appended claims.

20 We claim as our invention:

1. In combination, a locomotive having a firebox, grates within said firebox, a tender for said locomotive, a conveyor conduit beneath said tender and extending forwardly
25 therefrom, the forward end of said conduit being enlarged and provided with a pair of openings, a conveyor screw within said conduit having its forward end enlarged and provided with an increased number of flights,
30 a pair of transfer conduits having their rear ends beneath said openings for receiving fuel by gravity from the enlarged portion of said conveyor conduit, the forward ends of said transfer conduits curving upwardly and ex-
35 tending through said grates into said firebox and means in said last named conduits for conveying fuel along said transfer conduits.

2. In combination, a locomotive having a fire-box, a tender, a conveyor for transfer-
40 ring fuel from said tender to said locomotive, a plurality of conduits extending from beneath the forward end of said conveyor to the rear corners of said firebox through the bottom thereof, means for advancing fuel along
45 said conveyor and conduits and means for projecting fuel forwardly and laterally from the forward ends of said conduits.

3. In combination, a locomotive having a firebox, a tender, a conveyor conduit beneath
50 said tender and extending forwardly there-
from, a conveyor screw in said conduit, a pair of transfer conduits extending diverg-
ently forwardly from said conveyor conduit and having their forward ends curved up-
55 wardly and extending into said firebox one in each back corner thereof, a fuel transferring screw in each of said transfer conduits, and a steam nozzle for directing a blast across the upturned ends of said conduits for distribut-
60 ing the fuel over the grates of said firebox.

4. In combination, a locomotive having a firebox provided with a grate, a tender, a fuel conveyor leading from the tender to the locomotive, a pair of conduits branching from
65 the conveyor and entering the firebox, one

at each of the back corners thereof, and means for advancing fuel through the conveyor and the conduits.

5. In combination, a locomotive having a firebox, means in a rear corner of said fire-
70 box for delivering fuel to said corner and elevating it to a substantial height above the normal level of the firebed in said firebox and a nozzle in said corner for scattering said fuel over the fire in aerial paths.

In testimony whereof we affix our signatures.

NATHAN M. LOWER.
L. EDWARD OSBORNE.
EDWIN ARCHER TURNER.
